UNITED STATES PATENT OFFICE.

EDWARD H. MCLOUD, OF COLUMBUS, OHIO, ASSIGNOR TO THE KINNEAR MANUFACTURING COMPANY, OF COLUMBUS, OHIO, A CORPORATION OF OHIO.

AUTOMATIC FIRE-RESISTING CURTAIN.

Application filed January 15, 1923. Serial No. 612,648.

This invention relates to the type of fire resisting rolling curtain that is normally held up ready for automatic closing operation by the release of fusible means acted on by nearby fire. As shutters after installation are rarely or never operated or tested their bearings may become corroded to such an extent as to prevent operation at the critical moment it is the object of the present invention to provide means whereby a quick initial blow is imparted to the curtain winding member in its unwinding direction, said blow caused and followed by the pressure of a spring to start the curtain downward to closing position. Other objects will appear from the disclosure herein.

The invention is embodied in the example herein shown and described, the features of novelty being finally claimed.

20 In the accompanying drawing—

Figure 1 is a vertical sectional view taken longitudinally of the curtain drum.

Fig. 2 is a detail mainly in elevation showing the impact member on a larger scale.

25 Fig. 3 is a cross section on the line III—III Fig. 2.

Fig. 4 is a cross section on the line IV—IV Fig. 2 showing the position of the impact lug in shutter raising or raised position.

30 Fig. 5 is a similar section showing the impact lug starting the curtain down.

In the views 6 designates the barrel or curtain receiving member upon which the curtain is coiled. One end of the barrel (the left hand end as shown in Fig. 1) is provided with a plug and is supported on a shaft 7 that in turn is supported in an end bracket 8 fastened to the wall of the building containing the opening to be closed by the curtain. The shaft 7 is capable of being turned on its axis but has fixed to its outer end a wheel 7^a provided at its rim with a series of perforations any of which receives a pin passed through a perforated lug 8^a cast on the bracket for holding it so that the wheel and shaft can be held in any of the several positions permitted by the holes. The inner end of said shaft 7 where it enters the barrel is provided with a coil spring 9 secured at one end to the shaft 7 and at its other end to a plug 10 secured to the barrel so that by turning the shaft 7 and placing it under tension and then fixing the wheel 7^a the desired degree of counterbalancing effect can be had on the curtain. In the present

instance the tension to be placed on the spring is intended to be only about sufficient to prevent violent descent of the curtain when it is liberated for closing as herein-after described. The plug 10 is centrally perforated and the shaft 7 extends therethrough.

The other end of the barrel is also provided with a plug as seen at 11 and is supported on a shaft 12. The inner portion of this shaft where it extends into the barrel has pinned to it a thick disk 13 having at its right hand side a lug 13^a adapted to engage alternately as hereinafter described the opposed ends of an arcuate boss 11^a on the inner face of the plug 11. The opposed ends of the arcuate boss are shown as separated by a space somewhat more than a quadrant so that the lug 13^a can be swung about that distance. The opposite face of the disk 13

is provided with similar lug 13^b that is engaged by a similar lug on the right hand one of a series of disks 14 identical with each other turning loose on the shaft 12.

Each of the three disks 14 is provided with a lug on its opposite face so that they are interengaging and by turning the left hand one of the disks all the disks can be turned until finally they are all brought into engagement—each one with the next—until the

movement is finally arrested by a relatively fixed part or lug as for example an end of the arcuate boss 11^a. Loose on the shaft 12 to the left of the left hand disk 14 is a collar or clutch member 15 having a lug 15^a to engage the left hand lug of the proximate disk 14 and connecting said clutch member and a collar 16 pinned to the inner end of the shaft 7 is a short coil spring 17.

The outer portion of the shaft 12 is provided with an escapement braking or retarding means at 18 adapted to prevent a too rapid descent of the curtain it not being necessary to show or describe in detail such mechanism because not a part of the present invention. The outer end of said shaft has affixed thereto a sheave 19 to which is connected the end of a cable 20 for winding up the shutter, said cable being provided with a fusible link 21 exposed at the proper point when the curtain is raised dividing the cable in case of fire and therefore releasing the shaft and curtain for closing. The other end of the cable can be wound on a drum 22 near the floor, said drum operated by a crank

23 and provided with a dog 24 for latching it when the curtain is coiled up on the barrel. The curtain is held up by the dog and can be designedly released at any time by 5 disengaging that member.

Let it be assumed that in practice that 10 six turns of the barrel are required to normally coil up the curtain, this coiling up being effected by the unwinding of the cable; about five and one half of these turns will bring the lugs of the clutch mechanism together and the other half turn will be 15 against the spring 17 thereby placing the lug 13^a in the position shown in Fig. 4 in which position the barrel is held by securing the cable. Upon the release of the barrel— 20 by release of the cable either manually or by undue heat—the lug 13^a whirls and strikes the arcuate lug 11^a with a sharp impact imparting an initial movement to the barrel loosening it if stuck by corroded bearings. In the downward movement of the 25 curtain the contacting lugs of the clutch members become separated because the motion of the shaft 12 is reversed.

The number of the intermediate disks 14 is proportioned to the length of the curtain, the number and their location being such that their lugs shall all be interengaged 30 when the curtain is nearly completely raised the complete raising being finally effected through the closed lugs and against the spring 17 which is thereby placed under tension in which condition of the parts the winding cable is fastened.

The forms of the parts can be varied without departing from the gist of the invention as claimed.

What I claim is:

- 40 1. The combination with a fire resisting curtain and winding drum therefor, of means for imparting an initial closing movement to the curtain including a spring, a rotary impact member to act on the drum to 45 impart rotary curtain unrolling motion thereto, and a plurality of interengaging members between said spring and impact member, said spring adapted to be placed under tension by the engagement of said interengaging members and of the impact member with the drum in the final winding up of the curtain thereon and thermally controlled means for holding said spring in a state of tension for operation in case of fire.
- 50 2. The combination with a fire resisting curtain and winding drum therefor, of means for imparting an initial closing move-

ment to the curtain including a spring, a rotary impact member to act on the drum to 60 impart rotary curtain unrolling motion thereto, and a plurality of independently rotatable but interengaging members between said spring and impact member, said spring adapted to be placed under tension by the engagement of said interengaging members and of the impact member with the drum in the final winding up of the curtain thereon and thermally controlled means for holding said spring in a state of tension for 65 operation in case of fire.

3. The combination with a fire resisting curtain and winding drum therefor and counterbalancig means for the curtain, of means for imparting an initial closing movement to the curtain including a spring, a rotary impact member to act on the drum to 70 impart rotary curtain unrolling motion thereto, and a plurality of interengaging members between said spring and impact member, said spring adapted to be placed under tension by the engagement of said interengaging members and with the impact member with the drum in the final winding up of the curtain thereon and thermally controlled means for holding said 75 spring in a state of tension for operation in case of fire.

4. The combination with a fire resisting curtain and winding drum therefor, of means for imparting an initial closing movement to the curtain including a spring and an impact member rotatable without movement in its axial direction and actuatable by 80 said spring to impart a starting blow to said drum, said spring adapted to be placed under tension when the curtain is finally wound on the drum, and thermally controlled means for holding said spring in a state of tension for operation in case of fire.

5. The combination with a fire resisting curtain and winding drum therefor, of means for imparting an initial closing movement to the curtain including a spring and a rotary impact member actuated to act 85 directly on the drum to impart rotary motion thereto, said spring adapted to be placed under tension by the engagement of said impact member with the drum in the final winding up of the curtain thereon and thermally controlled means for holding said impact spring in a state of tension for 90 operation in case of fire.

EDWARD H. McCLOUD.
